UNITED STATES PATENT OFFICE.

JAMES P. HOLMES, OF OCEAN CITY, NEW JERSEY.

REINFORCED-CONCRETE PILING.

942,142.

Specification of Letters Patent. Patented Dec. 7, 1909.

Application filed February 5, 1902. Serial No. 476,223.

To all whom it may concern:

Be it known that I, JAMES P. HOLMES, a citizen of the United States, residing at Ocean City, in the county of Cape May and State of New Jersey, have invented certain new and useful Improvements in Reinforced-Concrete Piling, of which the following is a specification.

My invention relates to improvements in reinforced concrete piling, the object of the invention being to provide a piling assembled in sections, as the pile is sunk, and insuring a perfect juncture between the sections, and a perfect lock of the sections when the pile is complete.

A further object is to provide improved means for guiding the pile sections together, and so shape the interior of the pile sections, that they will be securely locked, and form in effect, a single integral pile when filled with cement after being sunk.

A further object is to provide an improved piling of this character which is especially adapted for use with connecting bars or sections, forming a continuous wall.

A further object is to provide an improved piling of this character, which can be readily braced and support a continuous wall made up of piling sections, against possibility of backward movement by the force of water.

With these and other objects in view, the invention consists in certain novel features of construction, and combinations and arrangements of parts as will be more fully hereinafter described and pointed out in the claims.

In the accompanying drawings, Figure 1, is a view in longitudinal section illustrating a preferred form of my improved pile. Fig. 2, is an end view of Fig. 1. Fig. 3, is a similar view of a slightly modified form of pile. Fig. 4, is an end view of Fig. 3. Fig. 5, is a fragmentary view in elevation of my improved piling wall. Fig. 6, is an end view of Fig. 5. Figs. 7, 8, 9, 10, 11 and 12, are views of other modifications.

My improved piling comprises a lowest section 1, and as many upper sections 2, as may be desired, to form a pile of any length. All of the sections are composed of concrete reinforced by metal inserts 3. The lowest section 1 is provided with a central pipe or tube 4, which latter extends throughout the length of the section, and is anchored therein by means of a cross bar 5, fast to the pipe, and the upper end of the pipe 4 which is

screw threaded, projects into a circular recess 6 in the upper end of section 1. This upper end of section 1 is also provided with a circular groove 7 at the upper end of its recess to receive a circular flange or tongue 8 on the lower end of an upper section, and form a neat joint between the sections. All of the upper sections 2 are cast hollow, and cored out at their ends, forming a recess 9, of approximately the same shape as the recess 6 in the lower section 1, so that when the pile sections are filled with cement, they will be effectually locked together by these adjacent recesses. The upper sections are all provided with central collars 10, connected to the sections by means of arms 11, embedded in the concrete wall, and longitudinal bars or strips 12 connect the collars 10, so as to prevent any lateral movement thereof.

In driving the lowest section 1, a pipe 13 is screwed onto the upper end of pipe 4, and water under hydraulic pressure is forced through the said pipes to displace the sand and gravel and allow the pile sections to sink. When this pile section has sunk partially, an upper section 2 is lowered onto section 1 by means of its collars 10, the collars 10 being positioned on the pipe 13, serve as guides to direct the section 2 into position over said section 1, so as to compel the tongue or flange portion 8 to ride into the groove portion 7 of the lower section and insure a perfect juncture of the sections. All of the upper sections are guided into position on the pipe 13 in this manner until the pile is of the desired length, when pipe 13 is turned to unscrew it from pipe section 4, the latter being held against turning by its anchor 5. When pipe section 13 is entirely removed, the pile is filled with cement, which when hardened, forms in effect, a continuous solid integral pile.

The advantages of a pile of this character are many. The pile sections can be made and transported from place to place with comparatively small expense, and can be assembled in close quarters, such as, under the floor of a building and the like, which needs pile strengthening, in which position, the ordinary form of pile could not possibly be used.

As shown in Figs. 3 and 4, the guide collars may be dispensed with, where the pile can be assembled above the water level.

In Figs. 5 and 6, I have illustrated two of

these piles, made with longitudinal dove-tailed grooves 14, to receive dove-tailed tenons 15, on the ends of concrete bars 16, which latter are sunk by means of jets of 5 water, and connect the piles to form a continuous wall.

In Figs. 7 and 8, I have shown a slight modification in which the piles are provided with parallel dove-tailed grooves 17 10 to receive the dove-tailed tenons 17^a, of narrow bars 18, and form, in effect, parallel walls, between which a filling of cement is to be provided, to provide a solid wall.

Figs. 9 and 10, illustrate a modified form 15 of connecting bar 20, which is cast hollow, and is adapted to be filled with cement.

In Figs. 11 and 12, I illustrate an improved manner of supporting a wall composed of pile, and bars as above explained, 20 in which a post or pile 21 is sunk into the ground and disposed at an angle, and this pile or post 21 and the piles 22 of the wall are provided with dove-tailed grooves 23 to receive braces or props 24, composed of concrete, and effectually support the wall, forming 25 a perfect breakwater, or other piling of this kind.

Other changes might be made in the general form and arrangements of parts described 30 without departing from my invention, and hence I do not restrict myself to the precise details set forth, but consider myself at liberty to make such changes and alterations as fairly fall within the spirit 35 and scope of my invention.

Having thus described my invention what I claim as new and desire to secure by Letters Patent is:

1. A pile comprising tubular sections, 40 having tongue and groove connection between them, said sections having enlarged recesses at their adjacent ends, adapted to receive a filling of concrete therein.

2. In a pile, the combination with a lower 45 section, of a pipe anchored in and extending through said lower section and having a screw threaded upper end, an upper section constructed to form a tight joint with the lower section, a removable water supply 50 pipe projected through the upper section and screwed onto the pipe in the lower sec-

tion, and collars carried by the upper section and movable on said removable pipe, to guide the upper section into position on the lower section.

55

3. A pile composed of sections of reinforced concrete, a water supply pipe anchored in and extending through the lowest section and projecting upwardly into a recess in the upper end of the lower section, a 60 tubular upper section constructed to fit upon the lower section, and having a recess in its lower end, a removable pipe constructed to pass through the upper section and connected with the pipe in the lower section for 65 the admission of water thereto, and said sections adapted to receive a filling of cement, locking them together to form a continuous pile.

4. A pile comprising tubular sections, 70 having tongue and groove connection between them, said sections having enlarged recesses at their adjacent ends adapted to receive a filling of concrete therein, and said sections having registering grooves in their 75 opposite faces, connecting bars, and tongues on said connecting bars adapted to enter the grooves in the piles to form a wall.

5. A pile comprising tubular sections, 80 having tongue and groove connection between them, said sections having enlarged recesses at their adjacent ends adapted to receive a filling of concrete therein, and said sections having registering grooves in their 85 opposite faces, connecting bars, and tongues on said connecting bars adapted to enter the grooves in the piles to form a wall, said pile sections having registering grooves midway between the first mentioned grooves, an inclined pile or post having a groove therein, 90 and props having tenons at their ends adapted to enter the last mentioned groove in said pile sections and in the inclined post or pile, substantially as and for the purpose set forth.

In testimony whereof I have signed my name to this specification in the presence of two subscribing witnesses.

JAMES P. HOLMES.
